UNITED STATES PATENT OFFICE.

HERMAN H. BINGER, OF LEWISTOWN, MISSOURI.

SILO-MOLD.

1,160,131.

Specification of Letters Patent. Patented Nov. 16, 1915.

Application filed August 20, 1915. Serial No. 42,882.

To all whom it may concern:

Be it known that I, HERMAN H. BINGER, a citizen of the United States, residing at Lewistown, in the county of Lewis, State of Missouri, have invented a new and useful 5 Silo-Mold; and I do hereby declare the following to be a full, clear, and exact description of the invention, such as will enable others skilled in the art to which it appertains to make and use the same.

This invention relates to an improved mold, for building concrete silos, cisterns and the like, and an object of the invention is to provide an improved sectional mold, including means for connecting the sections 15 tightly together.

Another object of the invention is to provide means for raising the mold sections, as one concrete tier is molded and becomes set, 20 in order to construct another section or tier of the silo superimposed on the first section or tier.

In practical fields the details of construction may necessitate alterations, falling 25 within the scope of what is claimed.

The invention comprises further features and combination of parts, as hereinafter set forth, shown in the drawings and claimed.

In the drawings:—Figure 1 is a view in 30 side elevation, showing parts in section, illustrating the invention in use. Fig. 2 is a vertical sectional view showing parts in elevation. Fig. 3 is a sectional view on line 3—3 of Fig. 1, showing parts in plan view. Fig. 4 is a detail view, showing portions of 35 two sections of the outer wall of the mold connected. Fig. 5 is a detail perspective view showing two sections of the inner wall of the mold. Fig. 6 is a vertical sectional 40 view through portions of the inner and outer walls of the mold, showing how the sections are connected. Fig. 7 is an enlarged detail perspective view illustrating how the sections of the inner walls of the 45 mold are connected.

When first starting to construct a silo or cistern, an excavation 1 is first formed in the ground, for the reception of the foundation wall 2 (which is constructed of concrete or 50 the like) of the silo or cistern. In constructing this foundation wall 2, only the sections 3 of the inner wall 4 of the mold may be used, or said foundation wall 2 may be constructed in any other suitable manner, if 55 desired. However, the foundation wall 2 has embedded therein annular tie rods 5, and

vertical rods 6, which vertical rods 6 are designed to extend upwardly and vertically to the entire wall of the silo or cistern. After constructing the foundation wall, the sections 7 of the outer wall 8 of the mold are placed in position, as shown in the drawings particularly Figs. 1, 2 and 3, above the foundation wall, then the sections 3 of the inner wall 4 of the silo mold or cistern are arranged concentric with the outer wall, as shown clearly in Figs. 1, 2 and 3. However, the inner wall of the silo or mold consists of upper and lower tiers 9 and 10, and each tier consists of the sections 4. The upper 70 and lower tiers are bolted together as shown at 11. The sections 4 of the upper and lower tiers of the inner wall have flanges 12, 13, and 14. The flanges 12 of the upper edge of the sections 4 of the upper tier of 75 the inner wall have overlapping parts 15, which are provided with openings 16. The flanges 13 have overlapping parts 17 provided with openings 18 similar to the openings 16, whereas the flanges 14 also overlap 80 and have openings 19. The under portions of the overlapping parts 15, 17 and 14 of said flanges 12, 13 and 14 are provided with inwardly extending lugs 20, through which the rods 21 extend. These rods 21 extend 85 through the strips 22, which are pivoted at 23 to the platform 24. The sections 7 of the outer wall of the silo have upper and lower outwardly extending annular flanges 25, which have overlapping parts 26 and 27. 90 The under parts 27 have laterally extending lugs 28, through which the rods 29 extend, which also extend through the strips 22. The overlapping parts 26 and 27 have registering openings 30, and threaded upon the 95 rods 21 and 29 are angular members 31 and 32. The arms 33 of the angular member 31 are V-shaped as shown in Fig. 7 clearly, and are designed to extend downwardly through the openings 16, 18 and 19 of said overlapping parts of the flanges 12, 13 and 14, thereby drawing the adjacent edges of the sections 4 of the upper and lower tiers of sections 4 of the inner wall together. 100

The arms 34 of the angular members 32 are tapered similar to the arms 33, and are designed to extend through the openings 30 of the overlapping parts 26 and 27 of the flanges 25 of the sections of the outer wall, so as to draw the adjacent edges of the sections of the outer wall together. To cause 110 the arms 33 and 34 to wedge through said

openings, to draw the sections of the inner and outer walls of the silo together, the rods 21 and 29 are rotated in one direction, and to withdraw the arms 33 and 34 from said openings, the rods 21 and 29 may be rotated in the opposite direction. However, the lower ends of the rods 21 and 29 have heads at their lower ends, as shown, and are provided with nuts 35 and 36 on their upper ends, to hold the strips 22 against the angular members 31 and 32, so that when the platform 24 is raised, the inner and outer walls of the silo will be correspondingly raised.

15 A suitable framing 37 is mounted on the bottom of the excavation 1, and this framing 37 consists of the four standards 38, which are angular in cross section, and braced by the bars 39, 40 and 41, and the angularly arranged tie rods 42. Mounted in suitable bearings of the upper ends of the standards 38 are pulleys 43. Mounted in bearings 44 of the lower brace bars 40 is a shaft 45 having a drum 46 and a worm wheel 47.

20 Mounted in bearings of the brackets 48 is a counter shaft 49 having a hand bar 50 and a worm 51, which worm meshes with the worm wheel 47. Connected to and wound about the drum 46 is a cable 52, the upper portion 30 of which has suitable connections 53 to the four cables 54, which pass over the pulleys 43, and are extended downwardly and connected at 55 to the outer portion of the platform, so that by turning the counter shaft 49, imparting movement to the shaft 45, through the worm and worm wheel connections, thereby imparting movement to the drum, the platform and the inner and outer walls of the silo or cistern mold, may be 40 raised. The raising of the platform and the inner and outer walls of the cistern or mold is accomplished subsequently to the construction of each tier of the silo or cistern. The framing 37 has a suitable ladder 45 60, whereby one of the operators of the apparatus may ascend to the top of the framing for adjusting any of the parts at the top of the apparatus. The framing is braced by the tie rods or cables 61. The upper portion 50 of the framing has a beam 62, at the end of which a suitable pulley 63 is suspended, over which a rope or cable 64 passes, which rope or cable, at one end, has a bucket 65, for hoisting cement, concrete or the like, in constructing the silo or cistern. As each tier of

the silo or cistern is constructed it is provided with annular tie rods or rings 66, similar to the rings 5, for reinforcing the wall of the silo or cistern.

The invention having been set forth, what is claimed as new and useful is:—

1. In a mold for silos, cisterns and the like, inner and outer walls concentric with each other and spaced apart, each wall consisting of sections arranged with their vertical edges adjacent each other and having overlapping flanges, said overlapping flanges having openings, members having tapering arms passing through said openings, and means threaded through said members to move the arms through the openings to draw the sections together.

2. In a mold for silos, cisterns and the like, inner and outer walls concentric with each other and spaced apart, each wall consisting of sections arranged with their vertical edges adjacent each other and having overlapping flanges, said overlapping flanges having openings, members having tapering arms passing through said openings, and means threaded through said members to move the arms through the openings to draw the sections together; a platform having connections with the upper edges of said walls, and means for raising the platform with the inner and outer walls attached.

3. In a mold for silos, cisterns and the like, inner and outer walls concentric with each other and spaced apart, each wall consisting of sections arranged with their vertical edges adjacent each other and having overlapping flanges, said overlapping flanges having openings, members having tapering arms passing through said openings, and means threaded through said members to move the arms through the openings to draw the sections together, a platform, links connected to the platform, and being in turn connected to the upper edges of the inner and outer walls by said means which adjust said members, and means for raising the platform and the inner and outer walls with the same.

In testimony whereof I have signed my name to this specification in the presence of two subscribing witnesses.

HERMAN H. BINGER.
